UNITED STATES PATENT OFFICE

FREDERICK D. PITTS, OF KANSAS CITY, MISSOURI

DESIGN FOR AN ELECTRIC HEATING ELEMENT BOWL

Application filed April 14, 1930. Serial No. 35,250. Term of patent 7 years.

To all whom it may concern:

Be it known that I, FREDERICK D. PITTS, a citizen of the United States, residing at Kansas City, in the county of Jackson and State of Missouri, have invented a new, original, and ornamental Design for Electric Heating Element Bowls, of which the following is a specification, reference being had

to the accompanying drawings, forming part thereof.

Fig. 1 is a front elevation of an electric heating element bowl, showing my new design. Fig. 2 is a side elevation of the same.

I claim the ornamental design for an electric heating element bowl, as shown.

FREDERICK D. PITTS.
